PROPELLER SHAPING MACHINE

John R. Albers, Sioux City, and Gerhard H. Albers, Cherokee, Iowa, assignors to Wincharger Corporation, Sioux City, Iowa, a corporation of Minnesota

Application October 28, 1935, Serial No. 47,190

5 Claims. (Cl. 144—134)

Our invention relates to a machine for shaping wooden propellers.

An object of our invention is to provide a shaping machine which efficiently shapes the propeller blades without the necessity of hand shaping.

10 A further object of our invention is to provide such a machine which will shape both the pitch and the airfoil curve of the blade merely by feeding a blank strip of wood through the machine.

15 A further object of our invention is to provide a machine of this type which will provide an accurate pitch and airfoil curve to the blade at all points along the surface thereof.

20 A further object of our invention is to provide such shaping means which will accurately shape the blade in spite of the gradual taper from the ends thereof to the hub portion.

25 A further object of our invention is to provide the above mentioned means in a machine of simple construction which can be manufactured at a reasonable cost.

With these and other objects in view, our invention consists in the construction, arrangement and combination of the various parts of our device, whereby the objects contemplated are attained, as hereinafter more fully set forth, pointed out in our claims, and illustrated in the accompanying drawings, in which:

30 Figure 1 is a side elevation of the machine,
Figure 2 is a plan view of the same showing the pitch cutter and the airfoil cutter,

Figure 3 is an enlarged sectional detail taken along the lines 3—3 of Figure 2,

35 Figure 4 is an enlarged detail in section taken along the lines 4—4 of Figure 2 and showing the cutting operation in advanced position,

Figure 5 is a section taken generally along the lines 5—5 of Figure 4,

40 Figure 6 is a similar section, except showing the airfoil cutting blades,

Figure 7 is an enlarged detail of the propeller dropping mechanism,

45 Figure 8 is a further view of the same, and Figure 9 is a plan view of the finished propeller.

The principal difficulties encountered in propeller shaping is that of attaining an accurate curve and pitch. The wooden propellers now made by hand are susceptible to human error, and it is our intention to show in our invention that we have provided a machine which will accurately cut the sectional contour of the blades with a minimum of time and effort. The difficulties encountered in any machine for cutting

wooden blades would principally reside in providing a correct airfoil curve regardless of the tapering thickness of the blade. We shall also show how we have accomplished this result.

We have used the character 10 to indicate generally the frameworks supporting the machine. The frameworks support the channel members 11, and it will be noted that there are two machines, one for cutting the pitch, and the other

5 10 15

the airfoil. Both machines are practically identical, with the exception of the differences which will be explained later, and therefore the description will apply to both types, with, of course, the exceptions noted. In Figure 2, it will be assumed that the lower machine is the one for cutting the pitch.

15 Affixed within the channel 11 are the two lengthened angle irons 12. In using the machine, first a flat rectangular strip of wood is cut out suitably with a band saw or by other

means to the shape as shown in Figure 9 which 20 is the flat surface shape of the finished propeller. Approximately one-half of the length of the propeller, or from one tip to the center, is bolted upon the platform member 13.

The platform member 13 is preferably made of wood, and includes the bevelled top 14, which bevel is the same as the pitch of the propeller. The flat

strip is indicated by the character 15 as shown 25 in Figure 3. Attached to the platform 13 is the substantially cylindrical member 16 which receives the further shaft 17.

The extremity of the shaft 17 is attached at one side to the square portion 18 and to the other end to the circular portion 19.

The circular portion 19 extends into the further square 20 which is integrally formed 30 therewith. The portion 19 (see Figure 7) extends into the ear 21 and also into the trip lever

22 which is slightly offset as shown in Figure 3. The trip lever 22 includes the bevelled ends 23

35 which terminate at a point as shown. To the ear 21 is affixed one end of the tension spring 24, the other end of which is affixed to the platform 13 at 25.

It will be noted that the square portion 20 and also 18 are set off-center, which provides an 45

important feature in the machine. A further strip 26, which is attached at 27 to the platform 13, acts as a stop member to limit the downward

movement of the trip lever 22. The forward end 50 of the platform 13 includes the further squared members 28 which are attached at the end

thereof, and the end of the member 13 also includes the keep-plate 29, which is attached thereto and which includes the small point members 30.

- The propeller shape, which has already been cut out, is now placed upon the platform or carriage 13, and the end is forced into the small points 30 in the keep-plate 29 (see Figure 4). 5
- 5 The U shaped clamp 31 is then brought over the strip 15 and is tightly clamped thereto by means of the cam lever 36 which is adapted to bear against the projections 77 of which there are two, which projections are rigidly attached 10 to the carriage 13. The carriage 13, which is now carrying the attached strip or blank form, is then fed into the machine by sliding the squared portions 18, 20, and the end square portions 28 along the angle irons 12. As the strip 15 is fed into the machine, it reaches the cutting members which will now be described. 15
- The cutting members on the pitch forming machine comprise the flat plates 37 which are rigidly attached to the square metal block 38 on opposite sides thereof. The plates are attached by means of the cap screws 39 which are received within the slots 76, which slots are lengthened for adjusting the cutting depth of the blades. 20 The plates 37 are bevelled at 41. The square blocks 38 extend into the integral shafts 40 which pass through suitable bearings 41 and 42, and the pulleys 43 are attached thereto. A semi-cylindrical housing 44 is attached about the cutting members and is spaced therefrom by means of suitable spacers 45, and is secured by means of the further bolts 46, which bolts pass into the enlarged angle member 47 which extends a fairly substantial distance above the channel member 11. 25
- 35 The blades are so adjusted that they will cut a suitable depth in the member 15 to provide the proper thickness of the blade, and of course are adjusted so that they both cut in the same circle, which circle is indicated by the character 48.
- 40 The member 13 is tapered slightly, and the square members 28 at the forward end of the carriage 13 support the platform 13 slightly above the level of the rear end so that the total result is that the carriage 13 tapers gradually downwardly towards the rear thereof. 45
- Both machines are run by means of the shaft 49 which is attached to the large pulley 50 and the other pulley 51. The shaft 49 is driven by means of the belt 52 which is suitably driven by means of an electric motor or other means. The belt 52 passes over the pulley 53, and surrounding both enlarged pulleys 50 and 51 are the further belts 54 which pass over the pulleys 43. It will be noted that the pulleys 43 are considerably smaller than the pulleys 51 so that a very high speed of rotation is imparted to the blade members 37. The circle of rotation of the blades is clockwise as shown in the drawings and against the direction of motion of the carriage 13. A chip breaker 60 is provided which comprises the plate 55 (see Figure 4) upon which rests a fairly heavy weight 56 to which is attached at 57 the tension spring 58, the other end of which is attached at 59 to the casing 44. The edge 60 of the plate 55 is placed 65 so that it just clears the rotating bevelled points 41 of the plates 37, and the function of this plate is to prevent the breaking off of large pieces which would tend to chip off from the wood, since it is placed close to the surface thereof and prevents such injurious effects. The plate 55 is attached to the post 61 which terminates in the bearing 62 which receives the end 63 of the U shaped member 64 which are in turn attached to the casing 44 at 65. The casings are cut away at 70 66 so that the weight will be received therein. 75

The spring 58 supports the plate 55 above the surface of the work.

Figure 4 illustrates the use of the carriage with the strip 15 attached thereto wherein the strip is being pushed through the machine by the operator. As it travels, the blades are cutting at a high rate of speed, and they cut the strip 15 along the surface 67 which is indicated also by the horizontal dotted line in Figure 3. As the carriage is forced through the machine, and by virtue of the sloping face 14 of the carriage, it will be seen especially from Figure 3 that a certain pitch is thereby cut on the propeller blade, since the member 15 is clamped upon the sloping surface of the carriage, and the pitch will be exactly the same as the slope 14. Also since the carriage 13 is high at the forward end, the thickness of the blade will taper from the end gradually to a larger thickness at the hub. As the carriage is forced through the cutting blades, the trip lever 22, of course, travels together with the same. A pin 68 is secured inside of the angle members 47 slightly above the center line of the machine. When the lever 22 strikes the pin (see Figures 7 and 8), it is carried over, as shown in Figure 8, and since the square portions 20 and 18 are off-center, they will rise to the position as shown in Figure 8, thereby causing the carriage 13 to drop downwardly within the channel 11. The pin 68 is so situated that this dropping action occurs as soon as the blades approach the hub portion of the propellers where, of course, it is not desired to cut. This dropping action then occurs, which causes the strip 15 to clear the blades so that the hub portion is left intact to its desired thickness. 35 After one blade of the propeller is cut, it is removed and then the other blade is clamped in the same position, and the operation is repeated, thereby providing an oppositely pitched slope on each blade, which pitch will be accurate from the tip to the hub. After the pitch is cut, the blade is then ready for the next operation which takes place in the airfoil cutter.

The airfoil cutter is the upper machine as shown in Figure 2, and is identical in every respect with the pitch cutter, with the exception of the blades and the slope of the carriage 13. A similar carriage 13 is employed in the airfoil cutter, with the exception that the carriage 13 in this instance is rectangular throughout its cross-section and does not include the slope 14, but instead the upper surface is horizontal. The carriage 13, however, tapers downwardly from the forward end to a more pronounced degree than in the pitch cutter, and which taper is indicated by the dotted lines 69. Attached to a similar block 38 are the blades 70 (see Figure 6), into which blades are formed the airfoil curve 71 having a suitable bevel 72. The curve 71 includes the smaller arcuate portion 73 and the lengthened airfoil curve 74. The curve portion 73 is at a substantial depth corresponding to or greater than the full thickness of the propeller blade. It will be seen from Figure 6 that as the carriage 13 travels past the cutting blades in the same fashion as in the pitch cutter, that first the thinnest portion of the blade will pass through the cutters. At this point, only part of the curve 73 and part of the curve 74 will cut off the material from the blade. Through the progressive travel of the carriage 13, however, the thicker portions of the blade will come next to the cutting curves so that as the blade varies in width, it also varies in thickness, and it will be noted especially from the curves that the curve will 75

accurately follow the thicker portion as well as the wider portion of the blades. As shown in Figure 6, the blade is in approximately its mid-position of cutting, and as the carriage is fed into the machine, the shape of blade will be cut as shown by the dotted lines 75, so that an accurate airfoil curve will be cut on the propeller, regardless of its increase in thickness and width. The same trip lever 22, with its associated mechanism, is employed in the airfoil cutter so that the hub portion will again be released from the cutting blades in the same manner. After the airfoil is cut on one blade or one-half of the propeller, it is removed, and the other end is clamped 15 to the carriage, and it is forced through the machine in the same manner.

The chip breaker plate in this instance is exactly similar to the other, with the exception that the edge 60, instead of being straight, is 20 curved to approximately the same curve as the curve 71 in the plate 70, so that the edge will perform the same function in preventing the breaking off of large pieces and will always be close to the cutting edges.

25 It will be understood throughout the description that besides explaining the mechanical arrangements for performing the operations, that we have provided a process also for shaping propeller blades, which process utilizes the principle 30 of accurately curved blades rotating at a high speed to cut the desired shapes.

It will now be seen that we have provided a machine for shaping wooden propellers, which shapes both the pitch and the airfoil curve of the 35 propeller, which provides an accurate pitch and airfoil curve at all points regardless of thickness or width, and which machine is of simple construction which can be manufactured at a very reasonable cost.

40 Some changes may be made in the construction and arrangement of the parts of our invention without departing from the real spirit and purpose of our invention, and it is our intention to cover by our claims any modified forms of 45 structure or use of mechanical equivalents, which may be reasonably included within their scope.

We claim as our invention:

1. An airfoil cutting machine comprising a channel, a carriage received within the channel, 50 means for attaching a propeller blank to the carriage, and means for cutting an airfoil curve on said blank mounted on said channel including a rotating block including an opposed pair of blades attached thereto having cutting edges substantially of the same contour as the airfoil curve 55 to be cut, said curve varying progressively along its depth and width so as to cut an accurate curve on said propeller regardless of the varying thickness and width of the same, said carriage sloping downwardly along its length on the upper 60 surface thereof to cause accurate cutting with respect to the tapering thickness of said propeller, means for dropping said carriage below the level of said cutting blades when above the hub portion 65 of the propeller including a pair of opposed guide members, a rotatable shaft attached at the inner end of said carriage, extensions eccentrically mounted on said shaft and received within the guide members, a trip member attached to said 70 shaft and to one of said extensions, a pin attached inwardly of said channel adapted to force said trip member pivotally about said shaft to cause the shaft to drop during forward movement of the carriage.

75 2. A pitch cutting machine comprising a chan-

nel, a carriage received within the channel, means for attaching a blank wood strip to the carriage, and means for cutting a propeller pitch on said blank strip mounted on said channel including a horizontal cutting member mounted on said channel, said carriage being sloped downwardly across its width on the upper surface thereof, said slope being the same as the pitch to be cut, and said carriage being higher at its forward end to accommodate the tapering thickness 10 of a propeller blade, means for dropping said carriage below the level of said cutting blades when above the hub portion of the propeller including a pair of opposed guide members, a rotatable shaft attached at the inner end of said carriage, 15 extensions eccentrically mounted on said shaft and received within the guide members, a trip member attached to said shaft and to one of said extensions, a pin attached inwardly of said channel adapted to force said trip member pivotally 20 about said shaft to cause the shaft to drop during forward movement of the carriage.

3. A pitch cutting machine comprising a channel, a carriage received within the channel, means for attaching a blank wood strip to the carriage, and means for cutting a propeller pitch on said blank strip including a horizontal cutting member mounted on said channel, said carriage being sloped downwardly across its width on the upper surface thereof, said slope being 30 the same as the pitch to be cut, and said carriage being higher at its forward end to accommodate the tapering thickness of a propeller blade, means for dropping said carriage below the level of said cutting blades when above the hub portion of 35 the propeller including a pair of opposed guide members, a rotatable shaft attached at the inner end of said carriage, extensions eccentrically mounted on said shaft and received within the guide members, means for rotating said extensions about said center to cause dropping of the carriage during forward movement thereof.

4. A pitch cutting machine comprising a channel, a carriage received within the channel, means for attaching a blank wood strip to the carriage, and means for cutting a propeller pitch on said blank strip mounted on said channel including a horizontal cutting member mounted on said channel, said carriage being sloped downwardly across its width on the upper surface 50 thereof, said slope being the same as the pitch to be cut, and said carriage being higher at its forward end to accommodate the tapering thickness of a propeller blade, means for dropping said carriage below the level of said cutting blades when 55 above the hub portion of the propeller including a pair of opposed guide members, a rotatable shaft attached at the inner end of said carriage, extensions eccentrically mounted on said shaft and received within the guide members, means for rotating said extensions about said center including a trip lever attached to the shaft, a pin attached to said channel for rotating said lever when forced thereagainst, to cause dropping of the carriage during forward movement thereof.

5. An airfoil cutter comprising a channel, a carriage received within the channel, means for attaching a propeller blank to the carriage, and means for cutting an airfoil curve on said blank mounted on said channel including a horizontal cutting member mounted on said channel having cutting edges substantially of the same contour as the airfoil curve to be cut, said curve varying progressively along its depth and width so as to 70 75

cut an accurate curve on said propeller regardless of the varying thickness and width of the same, said carriage sloping downwardly along its length on the upper surface thereof to cause accurate cutting with respect to the tapering thickness of said propeller, means for dropping said carriage below the level of said cutting blades when above the hub portion of the propeller including a pair of opposed guide members, a rotatable shaft attached at the inner end of said

carriage, extensions eccentrically mounted on said shaft and received within the guide members, means for rotating said extensions about said center including a trip lever attached to the shaft, a pin attached to said channel for rotating said lever when forced thereagainst to cause dropping of the carriage during forward movement thereof.

JOHN R. ALBERS:
